CYRUS J. BRISTOL, OF DES MOINES, IOWA, ASSIGNOR TO GLOBE MACHINERY & SUPPLY COMPANY, OF DES MOINES, IOWA, A CORPORATION OF IOWA

SAFETY LATCH FOR AUTOMOBILE LIFTS

Application filed September 23, 1929. Serial No. 394,459.

There has recently gone into quite extensive use a type of automobile lifts for use at automobile service stations, which lifts include a centrally arranged upright cylinder with a piston movably mounted therein and having a track at the top to receive the automobile wheels. The pistons are usually elevated by oil below the piston and within the cylinder, which oil is actuated by air under pressure with which service stations are generally equipped for tire inflating purposes and the like.

In connection with lifts of this general type it sometimes happens that the oil for supporting the piston in its elevated position may leak out and permit the piston to lower, and this might result in injury to an operator working on the under side of an automobile carried by the lift device.

The object of my invention is to provide an automatic safety latch device of simple, durable and inexpensive construction to be applied to the pistons of these lifts, and which is so arranged that when the piston is in its elevated position it cannot be lowered, even though all the oil below the piston should leak out, until the piston is again elevated, which can only be done by having the space below the piston filled with oil, and then the operator manually operates a latch device for withdrawing the latch to permit the lowering of the piston; and

Further in this connection it is my object to provide a latch device of this character which will automatically be released as soon as the slide bolts have passed below the top of the cylinder, so that in the event that the piston is lowered only a slight degree or the entire distance below its elevated position and again raised, the latch device will prevent its downward movement until such time as the latch is again manually released.

My invention consists in the construction, arrangement and combination of my improved latch device and its application to a piston and cylinder of the character described, whereby the objects contemplated are attained, as hereinafter more fully set forth, pointed out in my claims, and illustrated in the accompanying drawings, in which:

Figure 1 shows a side elevation partly in section illustrating a piston and cylinder of the character to which my improvement is applied, the upper end of the piston and cylinder and my improved latch device being shown in vertical section.

Figure 2 shows a vertical, central, sectional view through the upper portion of a cylinder and piston having my improved latch device applied thereto, and shown by solid lines in position for locking the piston against downward movement. In this figure there is shown by dotted lines the latch actuating device in position for holding the latch in its withdrawn position, and also in the lower portion of the figure I have illustrated by dotted lines the position of the latch device when it has passed below the top of the cylinder and has been moved to its extended position.

Figure 3 shows an enlarged, detail view showing a portion of the piston and cylinder with my improved latch device therein, the latch being shown in position where it has been released by the inward movement of the slide bolt; and

Figure 4 shows a sectional view on the line 4—4 of Figure 2.

Referring to the accompanying drawings, I have used the reference numeral 10 to indicate the cylinder having at its top a flange 11. This flange projects inwardly farther than the interior of the cylinder, and at its inner top edge is preferably formed with a rib 12. The flange is firmly secured to the cylinder by the bolts 13. The piston is indicated generally by the numeral 14 and has a packing 15 at its lower end to fit the interior of the cylinder and to prevent oil from passing upwardly beyond it.

The flange 11 forms a guide for the top of the piston and the body of the piston from the packing 15 upwardly stands spaced apart from the interior of the cylinder, thus preventing oil from being transmitted from the interior of the cylinder to the exterior of the piston, and hence that portion of the piston which projects above the cylinder is always free from oil.

Mounted within the piston is a frame 16 having a cross piece 17. Pivoted to this cross piece 17 are two arms, each composed of two parts 18. Between the parts of the lower end 5 of each arm there is pivoted a slide bolt 19, and this slide bolt is projected through and slidably mounted in an opening 20 in the cylinder 10. The upper portion of the slide bolt is beveled downwardly and outwardly at 21, and the lower portion of the outer end is beveled downwardly and inwardly at 22, for purposes hereinafter made clear.

The upper ends of the arms 18 are connected by contractile coil springs 23 yielding- 15 ly holding them toward each other, and at the upper end of each of the arms 18 there is a pin 24.

A latch plate 25 is mounted above the cross piece 17 with its lower end portion extending 20 between the parts of the arms 18. This latch plate is fixed to a handle 26 which projects upwardly to a point above the hollow piston where it may be conveniently reached by an operator.

25 The latch plate 25 has its side edges inclined downwardly and outwardly at 27, and in each side thereof there is formed a notch 28. The handle 26 extends below the cross piece 17 and is provided with a slot 29 to receive a pin 30 fixed to the cross piece 17 for guiding and limiting the movement of the latch plate 25.

In practical operation and assuming that 35 the parts of the device are in the position shown by solid lines in Figure 2, then obviously the downward movement of the piston is prevented by the slide bolts 19, which engage and rest upon the rib 12 surrounding the upper end of the cylinder, and when the 40 device is in this position, an operator may freely work around an automobile supported on the lift device without any danger of having the lift device and automobile move or fall downwardly, even though the oil which 45 normally supports the piston in an elevated position should leak out.

When it is desired to lower the piston, the operator must first elevate the piston a 50 slight distance, because normally ordinarily the weight of the automobile and lift upon the slide bolts resting upon the rib 12 is so great that the slide bolts cannot be withdrawn until this weight is removed from the slide bolts, 55 and this can only be done by elevating the piston.

After the piston has been elevated a slight distance, then the operator pulls upwardly 60 upon the handle 26. This moves the latch plate 25 upwardly and the engagement of the inclined edges 27 thereof force the pins 24 outwardly, thereby withdrawing the slide bolts 19 inwardly, and this movement continues until the pins 24 enter the notches 28, where- 65 upon the parts are locked in this position, and

this position is indicated by dotted lines at the upper portion of Figure 2.

Attention is called to the fact that when the slide bolts are in this partially withdrawn position, the inclined portions 22 of the slide 70 bolts are directly above the rib 12.

When this operation has been performed, the operator may release the handle 26 and then by permitting the escape of air, the oil in the cylinder is lowered and the piston may move downwardly. When the slide bolts 19 engage the rib 12, then on account of this engagement, and on account of the inclined surfaces 22 of the slide bolts, the slide bolts are automatically moved inwardly, and this inward movement of the slide bolts releases the pins 24 from their engagement in the notches 28, whereupon the latch plate 25 moves downwardly by gravity until it rests upon the cross piece 17, whereupon the slide bolts 19 are free 80 to be moved outwardly by the springs 23.

In the event that after the piston has moved downwardly to position with the slide bolts 19 below the top of the cylinder, the operator should again apply air pressure to the device and raise the piston, then the slide bolts 19 will, as soon as they get above the rib 12, move outwardly to position for again locking the piston in its upright position without any 90 attention on the part of the operator.

From the foregoing it will be seen that I have provided a manually operated means for locking the slide bolts in a withdrawn position to permit the piston to move downwardly within the cylinder, and that this manually operated means can be actuated only when the slide bolts are above and out of contact with the upper portion of the cylinder, and the only manner in which the piston can be so positioned is when there is 100 oil under pressure below the piston.

It will also be seen that I have provided a means actuated by downward movement of the piston for automatically releasing the slide bolts from their withdrawn position, so that in the event that after the slide bolts have passed below the rib 12, the operator should again raise the piston, the slide bolts will automatically assume their locked position without any attention whatever on the 110 part of the operator.

In the event that when the piston is at the bottom of the cylinder, an operator should move the latch plate 25 upwardly, and thereby lock the slide bolts in their partially withdrawn position, then when the piston is elevated the inclined portions 21 of the slide bolts will engage the lower edges of the flange 11, and thereby move the upper ends of the arms 18 outwardly so that the pins 24 release 120 from the notches 28, and the latch plate 25 will then drop by gravity to position for releasing the slide bolts.

By placing my improved latch device with- 130 in the interior of the hollow cylinder near

its lower end, and by extending the handle for operating it up through the hollow cylinder, I have provided a very convenient and inexpensive structure in which the parts are 5 all prevented from accidental movement or injury.

I claim as my invention:

1. In a device of the class described, the combination of an upright cylinder, a piston 10 movable within the cylinder, and a spring actuated slide bolt carried by the piston and yieldingly held in an extended position to engage the top of the cylinder and prevent downward movement of the piston, manually 15 operated means for locking the slide bolt in a withdrawn position to permit the piston to move downwardly within the cylinder, and means actuated by the movement of the piston for automatically releasing the slide bolt 20 from its withdrawn position.

2. In a device of the class described, the combination of an upright cylinder, a piston movable within the cylinder, a spring actuated slide bolt carried by the piston and yield- 25 ingly held in an extended position to engage the top of the cylinder and prevent downward movement of the piston, manually operated means for locking the slide bolt in a withdrawn position to permit the piston to 30 move downwardly within the cylinder, means actuated by the movement of the piston for automatically releasing the slide bolt from its withdrawn position, said means includ- 35 ing a beveled portion on the slide bolt positioned to co-operate with the top of the cylinder when the piston is moving downwardly with the slide bolt in its said withdrawn position.

3. In a device of the class described, the combination of an upright cylinder, a piston 40 movable within the cylinder, two arms pivotally supported within the piston, a slide bolt carried by each arm and projecting through the piston to engage the top of the cylinder, each slide bolt having its outer end at the upper portion thereof beveled downwardly and outwardly, and at the lower portion thereof beveled downwardly and inwardly, a spring for normally holding the arms 45 in position for moving the slide bolts to their projected positions, a manually operated locking device for moving the slide bolts to a partially withdrawn position where the inclined portions at the lower sides of the 50 slide bolts will engage the inner top edge of the cylinder to thereby further withdraw the slide bolts when the piston moves down through the top of the cylinder, and means actuated by said inward movement of the 55 slide bolts for releasing said locking device.

4. In a device of the class described, the combination of an upright cylinder, a flange at the top of the cylinder projected inwardly, a piston movable within the cylinder and 60 engaging said flange, two arms pivotally sup-

ported within the piston, a slide bolt carried by each arm and projected through the piston to engage the top of the cylinder, each slide bolt having its outer end at the upper portion thereof beveled downwardly and outwardly, and at the lower portion thereof beveled downwardly and inwardly, a spring for normally holding the arms in position for moving the slide bolts to their projected positions, a manually operated locking device for moving the slide bolts to a partially withdrawn position where the inclined portions at the lower sides of the slide bolts will engage the inner top edge of the cylinder to thereby further withdraw the slide bolts when the piston moves down through the top of the cylinder, and means actuated by said inward movement of the slide bolts for releasing said locking device.

5. In a device of the class described, the combination of an upright cylinder, a piston movable within the cylinder, a slide bolt carried by the piston and yieldingly held in an extended position to engage the top of the cylinder and prevent downward movement of the piston, manually operated means for locking the slide bolt in a withdrawn position to permit the piston to move downwardly within the cylinder, and means actuated by the movement of the piston for automatically releasing the slide bolt from its withdrawn position.
